UNITED STATES PATENT OFFICE.

WILLIAM A. GEIGER, OF CHICAGO, ILLINOIS, ASSIGNOR TO WILLIAM H. MINER, OF CHAZY, NEW YORK.

ADJUSTABLE YOKE.

1,286,277.

Specification of Letters Patent.

Patented Dec. 3, 1918.

Application filed June 9, 1917. Serial No. 173,842.

To all whom it may concern:

Be it known that I, WILLIAM A. GEIGER, a citizen of the United States, residing at Chicago, in the county of Cook and State of Illinois, have invented a certain new and useful Improvement in Adjustable Yokes, of which the following is a full, clear, concise, and exact description, reference being had to the accompanying drawings, forming 10 a part of this specification.

This invention relates to improvements in adjustable yokes.

As is well known, the draw bars now in use on railway cars while of standard form, 15 are of different sizes, due to the fact that the sizes of the draw bars have been increased in recent years to better take care of the heavier shocks imposed in actual service. The standard draw bars in service are generally 20 of three sizes, that is, having the butts thereof of 6½", 8" and 9¼" in height. All of these draw bars are, of course, provided with the usual standard upper and lower shoulders on the butts for engagement with 25 shoulders on the yokes when such shoulders are provided and all standard draw bars are also provided with a pair of vertically extending holes adapted to accommodate rivets or bolts. Some of the standard draw 30 bars are provided with coupler-key slots whereas many thousands now in service are not so provided. During recent years, there has been a constant tendency in the development of draft rigging art, to provide detachable draw bar and yoke connections and 35 while many attempts have been made to solve this problem, so far as I am aware, no one has ever heretofore designed a yoke which is adjustable and adapted for attachment to any standard draw bar regardless 40 of its size and regardless of the presence or absence of a coupler-key slot.

One object of my invention is to provide 45 a yoke adapted for shouldered engagement with the usual shoulders of any size standard draw bar butt.

Another object of my invention is to provide 50 a yoke of the vertical type which is adapted for adjustment to co-operatively engage any size draw bar butt.

Another and more specific object of my invention, is to provide a multiple piece yoke having means permitting adjustment of the 55 parts thereof to thereby accommodate the

yoke for co-operation with draw bars of different sizes. 55

In the drawing forming a part of this specification, Figure 1 is a side elevation of a draw bar butt and yoke showing my improvements in connection therewith, the inner dotted lines of the draw bar butt representing a smaller size than the butt which is shown in actual engagement with the yoke. Fig. 2 is a transverse, vertical sectional view, taken substantially on the line 60 2-2 of Fig. 1. Fig. 3 is a rear end elevational view of the improved yoke shown in Fig. 1. Figs. 4 and 5 are views corresponding, respectively, to Figs. 1 and 2 but illustrating another embodiment of my improvement. 65 70

In said drawing, referring to the structure illustrated in Figs. 1, 2, and 3, 10 denotes the shank of a standard draw bar having the usual butt at the rear end thereof, 75 said butt being provided with the upper and lower shoulders 11 and 12. The improved yoke, designated generally by the reference A, is shown as comprising an upper member 13 and a lower member 14, the same being 80 preferably counterparts in order to minimize the cost of production. Each of said parts comprises a horizontally extending arm, as shown, a vertical extension 15 at the rear end, side wings or walls 16 and 17 at 85 the forward end, and a transversely extending shoulder or gib 18. The extensions 15 on the rear of the members 13 and 14 are disposed as most clearly illustrated in Fig. 3, and each is preferably roughened on its 90 inner face, as indicated at 19, so that, when the two parts are drawn into tight engagement, as by a bolt 20 and nut 21, the parts are prevented from accidental relative vertical movement. Each of the extensions 15 95 is provided with a diagonally extending slot 22 in order to accommodate said bolt 20 and, as will be obvious, as the two elements 13 and 14 of the yoke are moved vertically relatively to each other, the bolt 20 will be 100 caused to travel inwardly and outwardly horizontally.

In the drawing, the yoke A is shown in its position adapted to co-operate with the largest size draw bar butt. The two elements of the yoke are fitted over the butt of the draw bar in the manner shown so that the shoulders or gibs 18 engage the shoul-

- ders 11 and 12 of the draw bar butt. In order to maintain proper engagement between the shoulders 18 and 11 and 12, each element of the yoke is perforated, as indicated at 23, 5 in line with one of the usual rivet holes provided in the draw bar butt so that a vertically extending elongated bolt 24 may be employed with a nut 25 to thereby hold the parts in proper engagement.
- 10 The dotted lines 26—26 in Fig. 1 indicate the upper and lower surfaces of a smaller sized draw bar butt, and the references 111 and 112 indicate the corresponding shoulders of said butt. As will be obvious, by loosening the nut 21 at the rear of the yoke sufficiently to permit the rear ends of the members 13 and 14 to slide over each other, the two parts of the yoke 13 and 14 can be drawn closer together into 15 proper engagement with the smaller sized draw bar butt and held in said position by the bolt and nut 24—25, and by tightening the bolt and nut 20—21.

With the arrangement above described, 20 it is apparent that my improvements are adapted for shouldered engagement with any size shouldered draw bar butt of standard form, whether the same is provided with a coupler-key slot or not, so that the improved yoke has a wide range of utility.

In the construction illustrated in Figs. 4 and 5, the general arrangement of parts is substantially the same as that illustrated in the other three figures. In this construction, however, the side wings 116 and 117 of the yoke elements 113 and 114 are provided with enlarged slots 30—30 of a length corresponding to the usual coupler-key 31 and of a vertical height sufficient to accommodate the full relative vertical movements of the yoke elements 113 and 114. This construction is more particularly adapted for standard draw bars having coupler-key slots and when the coupler-key is used, an additional engagement is provided between the draw bar and yoke through the coupler-key which engages the side wings of the yoke. At the rear end, the vertical extensions 115—115 are provided with vertical slots 122 to accommodate the bolt 120.

As an additional feature and to eliminate the use of a vertical bolt passing through the draw bar butt, should this be desired, the yoke shown in Figs. 4 and 5 has the side wings thereof provided with diagonally extending slots 32 and 33 which overlap each other and are adapted to accommodate short bolts 34—34. The inner wings 116 of the yoke members are preferably provided on

their inner faces with elongated counter-sunk grooves 35 to accommodate the heads of the bolts 34 so that the latter may lie flush with the inner surfaces of the yoke. With the arrangement of bolts 34, above described, it is obvious that the two yoke 65 elements can be locked in any adjusted position by merely tightening the nuts 36 thereon and the use of a vertical bolt extending through the draw bar is thereby eliminated.

From the preceding description, it will be seen that the yoke which I have provided is of simple form, may be readily and cheaply manufactured, and is adapted for cooperation with various size draw bars. 75 At the same time, the arrangement of yoke is preferably such that a hollow hood is provided at the forward end thereof to inclose the butt of the draw bar.

I claim:

1. A yoke for railway draft riggings comprising an upper arm and a lower arm, said arms having overlapping extensions at their rear ends, means for securing said overlapped extensions in adjusted positions, 85 each of said arms being provided at its front end with a shoulder arranged to engage a shoulder of a draw bar butt.

2. A yoke of the vertical type for draft riggings, said yoke comprising two counterpart members each of which is provided with a horizontally extending arm with a vertical extension at its rear end and a transverse shoulder at its forward end, and means for adjustably securing said extensions together.

3. In a device of the character described, the combination with a shouldered draw bar having a vertically extending opening therethrough, of a yoke comprising an upper and a lower arm, said arms being adjustably connected at their rear ends and provided at their forward ends with portions extending over the top and bottom portions of the draw bar butt, said portions being provided with perforations in alignment with said openings in the draw bar, and means penetrating said aligned openings of the draw bar and yoke and adapted to retain the forward ends of the yoke arms in place, the forward ends of the yoke arms being also provided with shoulders arranged to engage the shoulders of the draw bar.

In witness that I claim the foregoing I have hereunto subscribed my name this 21st day of May, 1917.

WILLIAM A. GEIGER.
